UNITED STATES PATENT OFFICE.

ARTHUR MCMASTER AND HENRY KEAN, OF HAMMOND, WISCONSIN,
ASSIGNORS OF ONE-THIRD TO FESTUS R. MONROE, OF HAMMOND,
WISCONSIN.

TIRE-TIGHTENER.

SPECIFICATION forming part of Letters Patent No. 720,174, dated February 10, 1903.

Application filed February 5, 1902, Serial No. 92,706. (No model.)

To all whom it may concern:

Be it known that we, ARTHUR MCMASTER and HENRY KEAN, citizens of the United States, residing at Hammond, in the county 5 of St. Croix and State of Wisconsin, have invented a new and useful Tire-Tightener, of which the following is a specification.

This invention relates to tire-tighteners.

The object of this invention is to provide a 10 novel form of clamp by which the ends of a tire and rim may be drawn together and held while a bridge is applied to the rim and felly.

With this and other objects in view, as 15 will appear as the nature of the invention is better understood, the same consists in the novel construction and combination of parts of a tire-tightener, as will be hereinafter fully described and claimed.

In the accompanying drawings, forming a 20 part of the specification, and in which like numerals of reference indicate corresponding parts, there is illustrated one form of embodiment of the invention capable of carrying the same into effect, it being understood 25 that the elements herein exhibited may be varied or changed as to shape, proportion, and exact manner of assemblage without departing from the scope of the invention, and in these drawings—

30 Figure 1 is a view in sectional elevation, exhibiting a section of a felly and tire with the bridge positioned thereon and a clamp for bringing the ends of the felly and of the tire together. Fig. 2 is a view in inverted plan 35 of the clamp. Fig. 3 is an end elevation looking in the direction of the arrow in Fig. 1, the felly, rim, and upper portion of the clamp being shown in section. Fig. 4 is a perspective detail view, partly in section, of the bridge 40 detached from the wheel. Fig. 5 is a fragmentary detail view in perspective, taken 45 from one end of the bridge.

In describing this invention the construction of the bridge will first be given, then 50 that of the clamp, and then the manner in which the bridge is applied to the wheel-rim and the manner in which the clamp operates to produce this result.

Referring to the drawings, and particu- 55 larly to Fig. 4 thereof, 1 designates the bridge,

the same to be constructed of malleable cast-iron, ordinary cast-iron, cast-steel, or of any other metal suited to the purpose. The bridge comprises a body portion 2, provided with two elongated bolt-openings 3 near the center thereof and at its ends with sockets 4 and with two hollow side wings 5, each provided with an elongated bolt-opening 6, the side wings being formed by two curved flanges 7, constituting a continuation of the walls of the sockets, and by the under side of plate 8 of the bridge, the said plate being extended beyond the flanges 7 to present tongues 9, that bear upon the under side of the rim, and thus additionally strengthen the same when the bridge is in position thereon. The bridge as a whole is shaped to conform to the curvature of the rim, and the body portion has its outer face provided with serrations or teeth 10, these being pitched in opposite directions from the medial line of the bridge and are designed to bite into the under side of the tire, thereby to hold the same against slipping when once adjusted. It is to be understood that this bridge may be 75 made and sold as an article of manufacture independently of any mechanism for positioning it upon a wheel, and for this reason it is to be understood that the bridge is not to be limited in its application to the combination with the specific form of clamp shown, and for a similar reason the clamp is not to be limited to coöperation with the specific form of bridge herein shown.

The clamp comprises two pairs of clamp- 80 arms 11, each provided on its outer side at one end with an orificed lug or boss 12 and on its inner side at the same end with a serrated clamping-jaw 13, this jaw by preference being detachably connected with the clamp-arm, as shown in Fig. 2, so that should the jaw become damaged in use it may be readily replaced by a new one. Coacting with each clamping-jaw is a tire-rest 14, the same comprising an L-shaped piece of metal 85 suitably secured to the inner side of the arm and operating, as shown in Figs. 1 and 3, to hold the tire in proper operative relation with the clamping-jaws. The pairs of clamping- 90 arms are drawn toward each other by operat- 95 100

ing-screws 15, which are right and left hand threaded and engage the orifices in the bosses 12, which are similarly threaded, the operating-screws being provided intermediate of their ends each with a squared portion 16 to be engaged by a wrench. The ends of the clamping-arms opposite those carrying the clamping-jaws are held assembled by bolts 17, carrying nuts 18, and on each of the bolts 17 is mounted a swivel-bolt 19, the opposed ends of which are respectively right and left hand threaded to be engaged by a turnbuckle 20, the bolts 19 and turnbuckle 20 constituting an adjustable brace-rod to hold 15 the two pairs of clamping-arms in rigid relation to each other when the operating-screws 15 are being turned to draw the opposite ends of the clamping-arms toward each other.

Intermediate of the ends of the clamping-arms there are provided bolt-openings 21, through which pass bolts 22, carrying springs 23, that bear against the opposed faces of the clamping-jaws and operate normally to press 25 the clamping-arms outward, each bolt 22 being provided with a nut 24, by which to move the clamping-arms toward each other against the tension of the springs 23 and cause the clamping-jaws to bite into the sides of the tire. To prevent the bolts 17 and 22 from 30 turning when the respective nuts thereof are tightened, the heads of these nuts are partly cut away to present a square surface 25, which engages with an abutment 26, carried by the outer side of two of the clamping-arms, 35 this arrangement being clearly shown in Fig. 3.

In applying the bridge in position upon a wheel the tire is first cut through, and then a length of the rim is removed to permit the 40 bridge to be brought into engagement with the ends thereof, the upper surface of the opposed felly-sections being cutaway to present a shoulder 27 to bear against the outer wall 28 of the socket and also to bring the rim 45 flush with the outer surface of the body portion. Holes are now drilled through the tire and the rim for the reception of bolts 29, that pass through the openings 6 in the bridge, and plates 30 are placed on the inner ends of 50 the bolts 27 to bridge the openings 6, after which the nuts 31 on the respective bolts are turned partly home. Openings are also drilled through the tire for the reception of bolts 32, which pass through the openings 3 in the bridge and carry at their inner ends plates 33, that bridge the openings 3, after which the nuts 34 of the respective bolts are turned partly home. The clamping-jaws 55 are then firmly secured against the sides of 60 the tire, as is shown in Figs. 1 and 3, and a

wrench is applied to the squared portions 16 of the operating-screws 15, thereby drawing the felly-sections and the tire-section to the required position, after which the nuts 31 and 34 are firmly seated, causing the teeth 10 to bite into the inner side of the tire and prevent separation of the rim and tire from each other. The nuts 24 of the bolts 22 are now loosened and the clamp removed from the tire.

It is to be understood that one or two of these 70 bridges may be applied to a wheel and also that instead of having the bolt-openings in the bridge elongated those in the tire and the rim may be elongated and still be within the scope of the invention.

75

Having thus fully described the invention, what we claim as new, and desire to secure by Letters Patent, is—

1. A clamp to be used for the purpose specified, comprising two pairs of clamping-arms 80 each carrying at one end a serrated clamping-jaw, a brace-rod for holding the clamping-arms assembled, clamp-adjusting screws arranged intermediate of the length of the arms, and means for moving the pairs of arms 85 to and from each other.

2. A clamp to be used for the purpose specified, comprising two pairs of clamping-arms each carrying at one end a serrated clamping-jaw, a brace-rod for holding the clamping-arms assembled, clamp-adjusting screws arranged intermediate of the length of the arms, and oppositely-threaded screws engaging threaded bosses on the said arms.

90

3. A clamp to be used for the purpose specified, comprising two pairs of clamping-arms each carrying at one end a serrated clamping-jaw, a brace-rod for holding the clamping-arms assembled, spring-carrying clamp-adjusting screws arranged intermediate of the 100 length of the arms, and means for moving the pairs of arms to and from each other.

95

4. A clamp to be used for the purpose specified, comprising two pairs of clamping-arms each carrying a detachable serrated clamping-jaw, tire-rests carried by the clamping-arms and disposed below the clamping-jaws, a brace-rod for holding the clamping-arms assembled, spring-carrying clamp-adjusting bolts arranged intermediate of the 105 length of the arms, and means for moving the pairs of arms to and from each other.

110

In testimony that we claim the foregoing as our own we have hereto affixed our signatures in the presence of two witnesses.
